J. B. Felskin

UNITED STATES PATENT OFFICE

2,473,025

BASEBALL GLOVE

Jon Gregg, New Hope, Pa.

Application August 2, 1946, Serial No. 687,848

3 Claims. (Cl. 2—19)

1

This invention relates to baseball gloves. It is particularly directed to a baseball glove for a child or boy.

An object of this invention is to provide an improved baseball glove which is so constructed that the child's hand will be protected against injury or hurt.

Another object of this invention is to provide in a glove of the character described, improved means to prevent the glove from being bent backwards should the glove receive a fast ball, whereby to prevent injury to the child's fingers.

Yet another object of this invention is to provide a strong, rugged and durable glove of the character described which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a front view of a glove embodying the invention;

Fig. 2 is a cross-sectional view taken on line 2—2 of Fig. 1;

Fig. 3 is a perspective view of one of the knuckle joints of the protective glove;

Fig. 4 is a view of one of the knuckle joints;

Fig. 5 is a view of a pair of adjacent knuckle rods spaced apart; and

Fig. 6 is a side view of the structure shown in Fig. 5.

Referring now in detail to the drawing, 10 designates a glove embodying the invention here shown in the form of a baseball glove particularly for children or young boys. The glove 10 comprises a front flexible wall 11 which may be made of leather or other suitable material. Stitched thereto is an inner flexible wall 12 forming therewith a pocket 13 to receive padding 15. Sheets or walls 11 and 12 may be stitched together at the bottom by a seam 16. They may be laced together at their outer edges by lacing 17.

Attached to the outer rim edge of walls 11 and 12 by means of said lacing 17 is a rear sheet 18 which may likewise be made of leather, forming with wall 12 a hand pocket 19 into which the hand of the player projects. The glove may be formed

2

with a thumb pocket as shown in Fig. 1 of the drawing.

Attached within the pocket 19 to walls 12 and 13 respectively as by lines of stitching 20 and 21 are flexible strips 22 and 23. The inner ends of said strips 22 and 23 are seamed together by a line of stitching 24 thereby forming a pocket 25. The line of stitching 24 may extend all around the glove. The seams 20 and 21 may follow the dotted line 21 shown in Fig. 1 of the drawing. It will be noted that pocket 19 is bound at the bottom.

The strips 22 and 23 may be stitched to walls 12 and 13 respectively, at the bottom by lines of stitching 27 and 28. The pocket 25 comprises a portion 25a located at one side of the glove, a portion 25b located at the opposite side of the glove, and a portion 25c located at the top of the glove. Within pocket portion 25 is a portion 30a of the protecting member 30. Said portion 30a comprises a plurality of rods 31. Each rod 31 is formed at its upper end with a slot 32, and at its lower end with a tongue 33. The tongue 33 of one rod is received in the slot 32 of the next adjacent rod. Rod 31 is formed with walls 35 on opposite sides of each slot 32. The walls 35 are formed with transverse aligned through openings 36. Tongue 33 is formed with an opening 37 registering with the openings 36. Said tongue 33 is formed with a rounded corner 38 at one side and with a square corner 39 at the opposite side. The square corner 39 is adapted to contact the bottom 40 of the slot or groove 32. Extending through the openings 36, 37 are hinge pins 44.

As shown in Fig. 3 it will be seen that the upper rod 31 may move in a counter-clockwise direction from its vertical position but not in a clockwise direction. The knuckles are so arranged that the glove may be bent forward but still not bent back beyond the vertical positions of the rods 31. The bottommost rod 31 is not formed with a tongue. The topmost rod 31 is formed with an upstanding pin 51. Engaging pin 51 and disposed within pocket portion 25c is a rod 52. Rod 52 is formed with a vertical opening at one end to receive the pin 51. It is formed at its opposite end with a groove 54 similar to groove 32, and is also formed with openings to receive a transverse pivot pin 55.

Connected to rod 52 is a rod 60. Rod 60 is formed with a tongue 61 at one end received within groove 54. The pivot pin 55 projects through opening in said tongue 61. At the opposite end 55 of rod 60 is a vertical through opening 63. It

will be noted that the rods 52, 60 are curved to conform with the shape of the top of the glove.

In pocket portion 25b is a vertical rod portion 30b likewise comprising a series of knuckle rods 31. The uppermost knuckle rod 31 is formed with a pin 51 received in opening 63 of rod 60. The lowermost knuckle rod 31 of said portion 30b is formed with a downwardly extending pin 65. Within the thumb portion of the pocket 25b is a U-shaped rod 66 formed with a through opening 67 to receive the pin 65. At the outer end of rod 66 is a tongue 68 pivotally connected to a rod 31. Said rod 31 may be connected to a plurality of such rods terminating adjacent the bottom of said pocket portion 25b.

All of the knuckle rods 31 are so constructed that the glove can be bent forwardly but not back beyond the vertical position of said knuckle rods.

Attached to rods 52, 60 and 66 are metal wings 70 projecting into opposite sides of the pocket 25 and serving to protect the tops of the fingers of the user of the glove. The wings 70 may be welded or otherwise secured to said rods.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A catching glove, and a protector within

said glove, said protector comprising rods inter-pivoted at adjacent ends, and extending around the periphery of the glove, said rods having knuckle joints to permit the glove to be bent forwardly but not back beyond a predetermined position, and wings on said protector located at opposite sides of the tips of the fingers of the user of the glove to protect said fingers.

2. A baseball glove comprising a pocket at the front, padding within said pocket, a pocket at the back to receive the hand of the user, a peripheral pocket within said glove, and an articulated series of protective knuckle jointed members within said peripheral pocket.

3. In combination with a glove, a hand protector therein comprising a rod formed with a tongue at one end, and a groove at its opposite end, and rods pivoted thereto, one receiving said tongue, and the other formed with a tongue received within said groove, said rods being inter-pivoted and disposed about the peripheral portions of the glove.

JON GREGG.
